UNITED STATES PATENT OFFICE.

MAURICE C. RYPINSKI, OF YONKERS, LE ROY W. STAUNTON, OF JACKSON HEIGHTS, AND STEPHEN BOURNE, OF NEW YORK, N. Y., ASSIGNEES TO BRANDES LABORATORIES, INC., OF NEWARK, NEW JERSEY, A CORPORATION OF NEW JERSEY.

DESIGN FOR A CONE SPEAKER.

Application filed March 10, 1926. Serial No. 16,867. Term of patent 3½ years.

To all whom it may concern:

Be it known that we, MAURICE C. RYPINSKI, LE ROY W. STAUNTON, and STEPHEN BOURNE, citizens of the United States of America, residing, respectively, at Yonkers, in the county of Westchester and State of New York, Jackson Heights, in the county of Queens and State of New York, and New York, in the county and State of New York, have invented a new, original, and ornamental Design for a Cone Speaker, of which

the following is a specification, reference being had to the accompanying drawing, forming part thereof.

The figure is a perspective view of the cone speaker showing our new design.

We claim.

The ornamental design for a cone speaker as shown.

MAURICE C. RYPINSKI.
LE ROY W. STAUNTON.
STEPHEN BOURNE.
